WALTER GLEDHILL, OF HOLMFIRTH, NEAR HUDDERSFIELD, ENGLAND

LOOM FOR WEAVING HAVING STATIONARY WEFT SUPPLIES

Application filed January 28, 1928, Serial No. 250,242, and in Great Britain February 4, 1927.

My invention in or relating to looms for weaving, has reference particularly to the type in which the use of a shuttle is dispensed with, the weft being drawn from a cheese or the like at one side of the loom and carried part way through the shed by one device, where it is handed over or taken possession of by another device which carries the end of the weft forward to the opposite edge of the fabric.

The object of my invention is to improve upon the construction of looms of this type as hitherto practiced, particularly in the direction of rendering possible the employment of any desired plurality of wefts of different colours or characteristics. Further features of the invention relate to the construction of the weft carriers and the mode of their operation; to the means for propelling and withdrawing said carriers; and to means for tying in or securing the ends of weft at each edge of the fabric so as to constitute selvages which will not fray.

In the accompanying drawings, illustrative of the construction of a loom according to the invention;

Fig. 1 is a plan view, and

Fig. 2 is a front elevation, of the delivering and receiving grippers by means of which weft, drawn from a stationary supply, is conveyed through the shed;

Fig. 3 is a front elevation of the grippers at the moment when, the grippers having met at the centre of the shed, the receiving gripper has closed upon the weft brought forward by the delivering gripper;

Fig. 4 is a plan view of the grippers showing the position when, the weft having been taken possession of by the receiving gripper, the grippers have commenced their outward movements towards the selvages of the fabric;

Fig. 5 is a front elevation of part of the right hand end of the loom, showing the means whereby the delivering gripper is re-

ciprocated; a similar mechanism being provided at the left hand end of the loom to reciprocate the receiving gripper;

Fig. 6 is a partial view of the gripper reciprocating mechanism shown in Fig. 5, the parts being shown in a different position and illustrating the manner in which a horizontal propelling movement is given to the gripper-reciprocating bar.

Fig. 7 is a partial plan view of the right hand end of the loom showing the parts in the position they occupy when the delivering gripper is approaching the outward limit of its reciprocation;

Fig. 8 is a similar view to Fig. 7, but shows the parts in the position they occupy when the delivering gripper has arrived back home and has closed again upon the weft; the inserted weft has been severed between the gripper and the selvage; and the severed weft end has been secured in the selvage;

Figs. 9, 10 and 11 are details illustrating the manner in which the severed weft ends are secured in the selvage;

Fig. 12 is a detail end view illustrative of the manner in which a delivering gripper is detachably secured to its reciprocating bar;

Fig. 13 is a side view, looking in the direction of the arrow A, Fig. 7, of the weft severing means;

Fig. 14 is a sectional end view of the carrier box wherein the delivering gripper is received at the end of its outward movement and which, together with the detachable connection between the delivering grippers and the gripper reciprocating bar, enables me to provide for the employment of any desired number of different wefts;

Fig. 15 is a detail illustrating in front elevation the means I provide for checking the receiving gripper at the end of its inward movement;

Fig. 16 illustrates, in elevation, means which may be employed in substitution for,

or in addition to the weft and securing means illustrated at Figs. 7 to 11;

Fig. 17 is a plan view, and

Fig. 18 a front view, of the means employed to open the receiving gripper when it has arrived at its outward limit of movement, so as to release the weft end and enable it to be secured in the selvage;

Fig. 19 is a front view and

Fig. 20 an end view of means for supporting a plurality of weft supplies and for taking up the slack which occurs between the delivering grippers and the supplies owing to the forward movement of the lay.

Fig. 21 is a partial front view of the right hand end of the loom, showing the position of the gripper checking means shown in Fig. 15.

Fig. 22 is a partial plan view of the right hand end of the loom showing the position of the slack take-up means illustrated in Figs. 19 and 20.

Fig. 23 is a partial end view, looking in the direction of the arrow in Fig. 22, showing the manner in which the lever 35 is operated.

Fig. 24 shows a diagram of a position of fabric, illustrating the manner in which the bill 56' turns in the weft ends to form a selvage.

Fig. 25 shows a portion of fabric, illustrating how two yarns may be twisted around the wefts and around the strong thread 57.

Fig. 26 shows a portion of fabric illustrating how two yarns may be twisted around the wefts to form a selvage.

Fig. 27 is a diagrammatic front view of the weft tying arrangement shown in Fig. 16.

I will first describe the means by which the weft is conveyed into and laid in the shed, and which may conveniently be referred to by the general term of gripper mechanism.

This mechanism comprises two members which I shall, for convenience of description, style respectively the "delivering" gripper and the "receiving" gripper, the delivering gripper being instrumental to take a weft end from a stationary supply and convey it part way across the shed, where it is met by the receiving gripper which takes possession of the weft end and carries it forward to the opposite edge of the fabric, thus completing the laying of a pick of weft in the shed.

The delivering gripper comprises a pair of jaws 1 and 2, pivoted together at 3, the points 1' and 2' of the jaws being fashioned to grip a weft end *w* between them as indicated in Fig. 1. On the inner side of the gripping surfaces the jaws 1 and 2 are bent or fashioned to form a recess 4, the purpose of which will appear later, and a lateral guide passage 5 is formed through the front jaw 1, through which the weft end may be passed into the recess 4 and thence between the gripping surfaces 1' and 2'.

65 A tail piece 6 on the jaw member 2 is formed

with two surfaces 6' and 6² arranged, as shown, at an angle to one another, and the shank 1³ of the jaw member 1 carries a bent spring 7 which is adapted to bear upon one or the other of the two surfaces 6' or 6² and thus hold the jaws closed as shown in Fig. 1 or open as shown in Fig. 4.

The shank 1³ of the jaw member 1 is detachably secured to a horizontal bar 8, a slot 1⁴ formed vertically in the rear side of the shank being adapted to receive a vertical projection 8' on the bar. The front side of the shank is formed with a longitudinal annular recess 8² (see Fig. 12) into which a correspondingly shaped spring member 9 secured to the bar 8 may enter, for the purpose of holding the shank in engagement with the projection 8' and pressed firmly against the face of the bar so that the gripper will reciprocate truly with the bar. The method of detachably securing the gripper shank to the carrier bar by means of the spring member 9 and of the projection 8' on the bar enables the gripper to be removed from its engagement with the bar, or to be re-engaged therewith, by a simple vertical movement of the gripper. This feature is of importance, as will appear later, in connection with the adaptation of the loom to the employment of wefts of different colours or characteristics.

The receiving gripper comprises a pair of jaws 10 and 11 mounted at 12 on a pivot stud extending forwardly from a longitudinal carrier bar 13 similar to the bar 8 which carries and reciprocates the delivering gripper. The ends of the jaws 10 and 11 are provided with respective gripping surfaces 10' and 11' and between these gripping surfaces and the pivot 12 the jaws are fashioned to present a recess 14 in the same way that the jaws 1 and 2 of the delivering gripper are fashioned to form the recess 4. The jaws of the receiving gripper are arranged to open in a direction at right angles to those of the delivering gripper, as will be apparent from Figs. 1 and 2. The inner end portions of the jaws of the receiving gripper are splayed or formed at an angle as indicated at 10² and 11², and the inner end portions of the jaws of the delivery gripper are tapered off as indicated at 1⁵ to form a nose which, as the two grippers are moved into contact, will engage between the surfaces 10² and 11² and force the jaws of the delivery gripper apart, against the action of a coiled spring 15 the ends of which are anchored in the shanks 10³ and 11³ of the respective jaws.

In order that the receiving gripper as it is moved inwardly into the shed, may not foul the warp threads, I provide on its front side a curved wire 16 which will engage the warp threads at a point somewhat nearer the fell of the fabric than the line of movement of the receiving gripper. The member 16 will thus operate to elevate or depress any warp threads

which may be out of line, and to hold them clear of the points of the gripper jaws. As a further safeguard in this direction, I preferably form the inward end of the carrier bar 13 for the receiving gripper with an enlargement or spear head 13' as indicated in Figs. 2 and 3. Any misaligned warp threads will be engaged by the angular faces 13², 13' of this enlargement or spear head and will be deflected clear of the gripper jaws.

The action of the grippers will be apparent from Figs. 1 to 4 and is as follows:—Figs. 1 and 2 assume that the delivery and receiving grippers are moving together or towards one another through the shed, the jaws of the delivery gripper having gripped between them the end W of weft and drawing from the stationary supply as the delivery gripper moves towards the centre of the shed. The grippers are arranged to meet at or substantially at the centre of the length of the shed, the receiving gripper being preferably timed to arrive slightly before the delivery gripper, so that when the latter arrives at its inward limit of movement the receiving gripper is positioned, and stationary, to receive it. As the tapered nose of the delivering gripper comes into contact with the surfaces 10² and 11² of the receiving gripper jaws, it forces said jaws apart and the nose passes into the recess 14, as indicated in Fig. 3, the gripping surfaces 10' and 11' of the receiving gripper closing down under the action of their spring 15 upon the weft end extending across the recess 4. The receiving gripper now commences its outward movement, slightly in advance of the delivering gripper. This causes the inner sides of the gripping surfaces 10' and 11', which are suitably shaped as indicated at 10⁴ and 11⁴, to be brought into contact with the respective jaws 1 and 2 of the delivery gripper, at the inner end of the recess 4. The action of the surfaces 10⁴ and 11⁴, in co-operation with the taper of the recess 4, is such as to force the movable jaw 2 away from the fixed jaw 1, as indicated in Fig. 4, the surface 6² being moved away from, and the surface 6' moved beneath, the end of the spring 7. The gripping surface 2' of the jaw 2 is thus held clear of the gripping surface 1' of the jaw 1. The grippers continue to move apart until they clear the selvages of the fabric, the receiving gripper drawing weft freely through the passage 5.

It will now be convenient to describe with the aid of Figs. 5 and 6 the means by which the carrier bars 8 and 13 are operated.

Gripper-reciprocating mechanism

As the mechanism for moving each of the carrier bars is similar, it will suffice to describe one mechanism, and that for moving the carrier bar 8 for the delivering gripper will be described. It may first be mentioned that each bar 8 or 13 is supported for horizon-

tal sliding movement in a horizontal guide such as 17 mounted on the lay or going part.

At its outer end the bar 8 is pivotally connected to the upper end of a picking stick 18, which carries at its lower end a roller 19 working in a vertical slot 20 in a bracket 20, fast with a rocker 21 pivoted to the adjacent end frame 22 of the loom. Pivotally mounted on a stud 23 on the rocker is a quadrant 24 which meshes with a toothed pinion 25 mounted on a stud 26 on an arm of the rocker 21. An arm 27 fast with the pinion 25 is pivotally connected with the stick 18 at 28. A connection 29, operated by a suitable crank motion at the centre of the loom is pivotally connected to the quadrant at 29'. The necessary "dwell" of the carrier bar, requisite for the change of shed and so on, is provided for by a plain or untoothed surface 24' on the quadrant, which co-operates with a plain segmental portion 25' on the pinion 25. As the connector 29 is drawn inwardly, it swings the quadrant, and causes the toothed portion thereof to be brought into mesh with the teeth of the pinion 25. The partial rotation given to the latter causes the arm 27 to swing downwardly, as indicated in Fig. 6, and the roller 19 on the stick 18 to move vertically downwards in the slot 20'. The pivot pin 18' by which the stick 18 is connected to the bar 8 is thus caused to traverse a true horizontal path and no strain is imposed upon the guide in which the bar works.

As above mentioned, the carrier bar 13 for the receiving gripper is operated by a mechanism similar to that just described for operating the bar 8. The connectors by which the quadrants of the two mechanisms are moved are preferably operated by a double crank at the centre of the loom, the crank arms being so set that the receiving gripper moves slightly ahead of the delivery gripper, as mentioned in the description of the gripper mechanism.

In order to check the inward movements of the grippers, I employ at each side of the loom a device such as illustrated at Fig. 15. This comprises a weighted disc 30 pivotally mounted on the lay and having pivotally connected to it at 31' a bar 31 having a curved end portion 31². A leather strip 32 secured at one end to the bar 31 has its opposite end bent as shown over the end of the curved bar portion 31², so that a space 33 is formed between the leather strip and the bar end. A pin 18', on the operating stick 18 of a gripper, is adapted to strike the leather strip 32 just before the gripper reaches its inward limit of movement. This causes the bar 31 to move inwardly and to rock the disc 30 about its pivot. The pivot centre of the disc, the point of connection of the bar to the disc, and the centre of the pin 18' being brought into alignment, the leather strip 32 acts to check further inward

movement of the stick and, consequently, of the gripper. The weight 30' of the disc operates to carry the disc past the dead centre and assists to commence the return or outward movement of the stick and gripper.

Outward movement of a gripper is checked by a strap 34 looped about the stick 18 and about a part of the lay or going part.

10 *Gripper opening and closing means*

As previously described, the delivering gripper makes its outward movement open, so that the receiving gripper may draw the weft freely through the passage 5. As it arrives back at the outward limit of its movement, it is necessary to close it again upon the weft, ready for the next inward movement. This is effected by means of a short lever 35 pivotally mounted, as at 35¹, at the back of the lay and having an engaging end 35' adapted, as the lever is swung appropriately about its pivot, to move forwardly and press against the open jaw 2 of the delivery gripper. The jaw 2 is thus closed upon the jaw 1 and the surface 6² brought beneath the spring 7, so that the jaw is maintained closed and a grip exerted upon the weft end. This closing movement is effected just as the gripper ceases to move outwardly, so that no pull is exerted on the weft end extending through the shed to the receiving gripper. The lever 35 is operated by the contact, with a depending projection 35² thereon, of a spring contact 36 on a bar 37 extending rearwardly from the breast beam 38. This spring contact yields after it has swung the lever 35 and passes beneath the lower end of the projection 35² as the lay continues its forward movement, a suitable spring 35⁴ on the pivot of the lever 35 acting to return said lever to normal position after it has performed its function. As the lay goes back, the contact 36 yields to permit of the passage over it of the projection 35².

45 The receiving gripper moves outwardly carrying the weft end it has taken over from the delivery gripper. It is necessary that, when the receiving gripper reaches its outward limit of movement, it shall relinquish its grip on this weft end, to permit of the inserted weft being beaten up, and to prepare it for its next inward movement to receive a new weft. The requisite opening of the jaws of the receiving gripper is effected by a member 39 pivotally mounted at 39' on the lay and having connected to it a radius rod 40 which works through a block 41 mounted pivotally on the breast beam. A collar 42 secured on the rod 40 abuts against the block 41 as the lay approaches front centre and causes the member 39 to swing inwardly. A rearwardly bent portion 39² of the member 39 is thus swung upwardly into a position to enter between the shanks of the receiving gripper jaws as the receiving gripper moves

outwardly, and forces the jaws open. As the lay goes back, the member 39 is swung outwardly by a suitable spring and the portion 39² thereof is moved from between the gripper shanks, permitting the gripper jaws to close again ready for the next inward movement.

70 I have now described the gripper mechanism and its operation, and the means by which the grippers are reciprocated and their jaws opened and closed. I will now describe the means by which the weft end is severed between the delivery gripper and the selvage of the fabric, and by which the ends of weft projecting beyond the edges of the fabric at 80 the respective selvages are dealt with.

75 *Weft-cutting and selvage forming means*

85 Mounted between the edge of the fabric and the outward position of the delivery gripper is a rotary cutter disc 43 into contact with which the weft is brought as the delivery gripper closes upon it and continues to move forwardly.

90 Rotation of the cutter disc 43 is effected as follows:—On its axis is a small pulley 44 about which passes a cord 45. One end of this cord is connected to a spring 46 anchored on the breast beam, and its other end is connected to one arm of a bell crank lever 47 pivoted at 48 to the support 43' for the cutter disc 43. The other arm of the bell crank 47 has a part 47' adapted to be engaged by an abutment 49 on the lay as the latter beats up. As a result of this engagement the lever 47 is rocked about its pivot and the cord 45 is drawn downwardly. This causes a rotation of the disc 43 and an extension of the spring 46. As the lay recedes, the contraction of the spring 46 draws back the cord 45 and returns the lever 47 to normal position; a stop 43⁴ on the support 43' limiting the movement of the lever 47. The rearward end of the support 43' has a slot 43² with a bell mouthed entrance 43³ to guide 100 the weft to be cut.

105 As the means for dealing with the projecting weft ends at the two sides of the loom are similar, it will suffice to describe one of them. That at the right hand end of the loom will, therefore, be described. The cap 50 of the temple 51 is formed with a block 50' having a cylindrical bore in which works a spindle 52. In the periphery of this spindle is formed a spiral groove 52' into which enters the point of a set screw 53 screwed into a threaded opening in the block 50' to project into the bore thereof. An annular groove 52² at the front end of this spindle receives the forked end of a spring blade 54 mounted on the breast beam; and an upwardly bent member 55 secured to the abutment 49 on the lay is adapted to engage the blade 54 as the lay beats up and to move the spindle 52 forwardly with a consequential partial 115 120 125 130

rotary movement. The rearward end of the spindle 52 carries a wire 56 the rearward end of which is curved and fashioned to form a bill 56' with a thread engaging extremity or hook 56². This bill 56' is positioned, as shown, above the edge of the fabric, and it is adapted when rotated and drawn frontwardly, to seize hold of the weft end, which at this moment is extending across and adjacent to the cutter 43, and to whip such end when severed into the shed and carry its extremity up between the upper warp threads of the shed at a short distance from the edge of the fabric, so that on the beat up it will be secured. In order that the bill may have something to offer the requisite resistance, about which to loop or turn in the weft end, I provide outside the warp edge a strong thread 57 independent of the warp and forming part of the selvage, and which can be raised and lowered by means of a suitably operated cam motion. The operation of securing the weft ends, and the function and operation of the strong thread 57 will be better understood by reference to Figs. 9 to 11 and 24. In Fig. 9 the weft W is shown as extending out through the open shed, the thread 57 being at this time lowered. The thread 57 is then raised as shown in Fig. 10 by a cam or other suitable motion, elevating the weft slightly as indicated and giving room beneath it and between itself and the lower warp threads for the passage of the engaging end of the bill (Fig. 7). As soon as the thread 57 has been raised, the spindle 52 receives its frontward and rotary movement, with the result that the weft end is brought into contact with the cutter and is severed and carried round beneath the raised thread 57 as a pivot, the extremity of the severed end being carried up as shown in Fig. 11 between two warp threads at a short distance inwardly from the edge of the fabric. The manner in which the engaging end of the bill passes down between the upper warp threads and beneath same and the strong thread 57, to take hold of the weft end as it is cut is shown in Fig. 7. The rear end of the groove 52' in the spindle 52 is made parallel with the spindle axis for a short distance, as indicated in Fig. 8, so that when the bill has whipped up the extremity of the weft end in the manner indicated it is drawn forwardly a short distance so as to be clear of the reed as the beat up takes place. As the lay recedes, the bill moves straight back for a short distance until the new shed has opened, and then rotates back to the position shown in Fig. 7 ready to deal with the next weft end. The mechanism for dealing with the weft ends at the opposite edge of the fabric is similar to that just described, with the exception, of course, that the spindle carrying the bill rotates in the opposite direction. The ends of the weft which project

above the fabric may be cropped off either on the loom or subsequently during the finishing of the fabric.

As an additional security in the direction of tying in the weft ends, the means illustrated at Fig. 16 may be employed, or such means may be employed alone for the purpose. The means referred to comprise a pair of bobbins 58 and 59 the spindles of which are carried by a chain or band 60 extending around a pin or roller 61 and a wheel 62, the latter receiving intermittent partial rotations by gears 63 and 64 from a star wheel 65 operated from a suitable moving part such as a jack or lever of the loom dobby. The threads 58' and 59' from the bobbins 58 and 59 are led through a ring 66 and then through eyes 58² and 59² in the ends of the respective bobbin spindles, after passing through which they are led around the stout thread 57 or around one or more of the warp threads at the edge of the fabric. Each operation of the star wheel 65 is arranged to reverse the positions of the bobbins 58 and 59 with the result that the threads leading from the bobbins are gradually drawn off and twisted around the thread 57 or such of the warp threads as may be concerned, between each insertion of weft, the weft ends being thus tightly gripped. The parts just described will conveniently be mounted in rear of the reed, and be carried say by a bracket attached to the loom frame. The thread 57 may pass through the ring 66, and for each step of the star wheel 65, the chain 60 moves through one-half of its circuit, thereby reversing the bobbins 58 and 59. This not only produces a half turn of the threads 58' and 59' around the thread 57, but the threads 58' and 59' are also alternately moved to opposite sides of the thread 57, similar to the formation of the warp shed, so that the wefts may pass between the threads 58' and 59'. The twisting of threads 58' and 59' will therefore tie the wefts to the thread 57, or similarly around one of the warp threads, the device shown in Fig. 16 being operable on the strong thread 57 or one or more warp threads, or may apply the threads 58' and 59' to the wefts only, as seen in Fig. 26. Fig. 25 shows the threads 58' and 59' twisted around the strong thread 57 and binding the wefts thereto.

The description so far applies equally to the employment of a single weft or to the employment of a plurality of different wefts. It only remains therefore to describe the means whereby the employment of a plurality of wefts is rendered possible.

Multiple weft arrangement

The use of a plurality of wefts is arranged for by providing at the right hand end of the loom a vertically movable carrier box 66 containing a number of superimposed cells 66' equal to the number of different wefts it is

desired to employ, and each adapted to receive a delivery gripper. Extending vertically through the box 66 is a fixed bar 67 provided, opposite the raceway or weft delivery line, with a notch 67' in its rear face of a depth to admit a delivery gripper. Each delivery gripper employed has in its front edge a notch 68 (see Fig. 1) corresponding in width to or slightly larger than the bar 67. 5 The box 66 is connected by a link 69 with suitable mechanism controlled by a dobby, pattern chain or the like, whereby the said box may receive vertical movements to present opposite the weft delivery line the cell 10 or chamber corresponding to the weft of the colour or characteristic called for. The box movements take place when the carrier bar 8 is in outward position, so that when by a 15 box movement the delivery gripper which has been active is detached from the spring holder 9 another delivery gripper is moved into position opposite the carrier bar and in so moving is engaged and held by the spring 9 in position over the projection on the carrier bar. 20 The engagement of the non-active delivery grippers, by the entry of the bar 67 into their vertical notches, holds them in the carrier box during their periods of non-activity and maintains them in correct position for 25 engagement with the carrier bar when called upon by the indications of the box pattern mechanism. Each delivering gripper draws its weft from its own source of supply, and it will be apparent that any number of cells 30 beyond the four indicated and additional delivering grippers may be provided according to the variety of colours or characteristics of weft it is desired to employ.

Where a plurality of wefts are employed, 40 or even where a single weft is employed, it is desirable to provide means to take up the slack, and consequent curl, of the weft which occurs during the beat up of the lay after the receiving gripper has ceased to draw off, and 45 the delivering gripper has closed again upon the weft. Figs. 19 and 20 illustrate one means for supporting and dealing with plurality of weft supplies.

A frame 70 adapted to hook over the breast 50 beam has a number of vertical spindles 71 corresponding to the number of wefts to be used. An inverted U-shaped member 72, pivoted to lugs 73, 73, on the breast beam, has a connection 74 to the lay. The ends of weft 55 from the several bobbins on the spindles 71 are led through guide eyes 75 and through openings 72' in the cross-bar of the member 72. As the lay swings forwardly and rearwardly, the member 72 swings with it, and 60 by its pivotal movement takes up the slack. The ends of weft extending from the member 72 are preferably led through a vertical guide 73' Figs. 7 and 8 secured to the carrier box 66 and provided with the requisite member 65 of appropriately spaced guide openings.

It will be apparent that, although the foregoing describes one good practical embodiment of the invention the details of construction and arrangement of the parts employed may obviously vary in many ways according to the kind of fabric to be woven and to suit individual requirements. 70

Having thus described my invention, what I claim as new and desire to secure by Letters Patent is:— 75

1. A loom having a pair of reciprocable members movable toward and away from one another, receiving and delivering weft grippers carried by said members, and means for checking the movement of the member which carries the receiving gripper comprising a rotary member and a bar pivoted to said member and having a portion for the contact of a portion of said member, said rotary member having a weight to turn it past dead center 80 when said bar is moved by said member. 85

2. A loom having a pair of reciprocable members movable toward and away from one another, a receiving weft gripper carried by one of said members, and a plurality of delivering weft grippers each attachable to and removable from the other carrying member transversely thereof. 90

3. A loom having a pair of reciprocable members movable toward and away from one another, a receiving weft gripper carried by one of said members, a plurality of delivering weft grippers, the other member having means for the detachable connection of the delivering weft grippers, and means for mounting the delivering weft grippers to selectively attach them to the last named member. 95

4. A loom having a pair of reciprocable members movable toward and away from one another, a receiving weft gripper carried by one of said members, a carrier box movable transversely of the other member, and a plurality of delivering weft grippers in said box, said delivering weft grippers and second-named member having portions for the attachment of the delivering weft grippers to the second-named member by the movement of the box transversely of said member to selectively attach the delivering weft grippers to said member. 105

5. A loom having a pair of reciprocable members movable toward and away from one another, a receiving weft gripper carried by one of said members, and a plurality of delivering weft grippers selectively attachable to the other member and each having a weft guide. 110

6. A loom having a pair of reciprocable members movable toward and away from one another, receiving and delivering weft grippers carried by said members, a cutter disk arranged for the contact of the weft adjacent to the delivering weft gripper in the outward limit of movement of said gripper, and means 115

for rotating said cutter disk by the approaching movement of said disk and delivering weft gripper.

7. In a loom, a weft engaging bill adjacent to the selvage of the cloth having a weft engaging hook, and means for projecting said bill between warp threads to engage said hook with the terminal of a weft and for retracting said bill to draw said terminal between said threads.

8. In a loom, a weft engaging bill adjacent to the selvage of the cloth and arranged to move between warp threads into the shed and having a hook to engage the terminal of a weft, and means for projecting said bill between the warp threads to engage said hook with a weft and for retracting said bill to draw the weft terminal into the shed and between said threads.

9. In a loom, a weft engaging bill mounted adjacent to the selvage of the cloth for turning and sliding movements and arranged to move between warp threads into the shed and having a hook to engage the terminal of a weft, and means for oscillating and sliding said bill to project it between the warp threads to engage said hook with the weft terminal when the shed is opened and to retract said bill for drawing said weft terminal into the shed and between said warp threads.

10. In a loom, a weft engaging member having a hook, and means for mounting and actuating said member for projecting it between warp threads into the shed to engage said hook with the terminal of a weft and for retracting said member to draw said terminal into the shed and between said threads.

11. A loom having a pair of reciprocable members movable toward and away from one another, receiving and delivering weft grippers carried by said members, the delivering gripper having a weft guide arranged to guide the weft through said gripper and to maintain the weft associated with said gripper, the grippers being constructed to cooperate whereby said grippers in meeting will cause the receiving gripper to grip the weft held by the delivering gripper and to open the delivering gripper as the grippers separate, the delivering gripper having means for holding it open, and means for closing the delivering gripper and opening the receiving gripper at the limits of their separating movements.

12. A loom having a pair of reciprocable members movable toward and away from one another, receiving and delivering weft grippers carried by said members and each comprising a pair of jaws, one jaw of the delivering gripper having a weft guide arranged to guide the weft between the jaws of said gripper and to maintain the weft associated with said gripper, the jaws of said grippers having cooperable portions whereby said grippers in meeting will cause the jaws of the

receiving gripper to grip the weft held by the delivering gripper and to open the jaws of the delivering gripper as the grippers separate, means for holding the jaws of the delivering gripper open, and means for closing the delivering gripper jaws and opening the receiving gripper jaws at the limits of the separating movements of the grippers.

13. A loom having a pair of reciprocable members movable toward and away from one another, a receiving weft gripper carried by one of said members, and a plurality of delivering weft grippers to be carried by the other member for cooperation with the receiving weft gripper, said delivering weft grippers being selectively attachable to said other member.

In testimony whereof I affix my signature.
WALTER GLEDHILL.
